UNITED STATES PATENT OFFICE

WALTER G. HEGINBOTTOM, OF FLINT, MICHIGAN, ASSIGNOR TO MARVEL CARBURETER COMPANY, OF FLINT, MICHIGAN, A CORPORATION OF INDIANA

HEAT-CONTROLLING MEANS FOR CHARGE-FORMING DEVICES

Application filed March 14, 1923, Serial No. 625,055. Renewed February 1, 1927.

This invention relates to certain new and useful improvements in heat controlling means for charge forming devices, the object being to provide novel means for controlling the application of heat to the charge forming device whereby the temperature of the charge can be regulated to a nicety in order to produce an explosive charge of high efficiency without any danger of overheating the charge throughout the entire range of operation of the engine under all atmospheric conditions.

Another object of my invention is to provide heat controlling means so constructed that when used in connection with an internal combustion engine that when starting the engine I am able to apply as large a volume of exhaust gases as desired for as long a time as desired to heat the charge, and so arranged that when the throttle is opened to any predetermined position from closed position to full open position, the means for controlling the application of heat will be operated so as to lessen the volume of the heating medium passing through the heat jacket.

A still further object of the invention is to provide means for allowing the charge throttling valve to move any predetermined desired distance before the exhaust throttling valve is moved, whereby the exhaust throttling valve will dwell on its seat while the throttle valve is moved a predetermined distance so as to hold the volume of exhaust gases in the heating chamber for heating the charge quickly while the engine is warming up.

A further object of the invention is to provide controlling means in the form of an adjustable cam so mounted and connected to the controlling means that the adjusted position of the cam determines the distance of movement the throttle valve is allowed to open before causing the exhaust throttle valve to be operated.

A still further object of the invention is to provide an additional valve having a connection with the cam so that the volume of exhaust gases delivered to the heat jacket will be regulated by the position of the cam.

Another and further object of the inven-

tion is to provide a construction which is exceedingly simple and cheap to manufacture and one which can be readily applied to any of the well known types of charge forming devices used in connection with internal combustion engines of various types whereby manually operated means is provided for setting the device so as to determine the movement of the controlling valves to regulate the application of the heating medium for heating the explosive charge and the air to produce said charge.

Other and further objects and advantages of the invention will be hereinafter set forth and the novel features thereof defined by the appended claims.

In the drawings,

Figure 1 is a side elevation of an internal combustion engine showing the application of my improved construction of heat controlling means thereto;

Figure 2 is an elevation on the opposite side to that shown in Figure 1 showing the cam and its manner of mounting and adjusting the same;

Figure 18 is a detail view showing the volume valve arranged at the inlet of the heat jacket;

Figure 19 is a side elevation showing an air heater for the charge forming device arranged over the outlet pipe of the heat jacket with the valve arrangement substantially the same as shown in Figure 4; and

Figure 20 is a side elevation showing an air heater arranged on the outlet pipe with the valve arrangement substantially as shown in Figure 6.

In the drawing 1 indicates an internal combustion engine, 2 the exhaust manifold, 3 the intake manifold and 4 a charge forming device connected thereto which is herein shown provided with a valve controlled air inlet 5 to which is connected a conduit 6 extending from an air heater 7 located around the end of the exhaust manifold 2, said conduit being provided with an additional valve controlled air inlet 8 for regulating the temperature of the air delivered to the charge forming device.

The charge forming device 4 is provided with a heating jacket 9 having an inlet 10 which is disposed under an outlet 11 of the exhaust manifold 2 and secured thereto in any desired manner so that the exhaust gases from the exhaust manifold will circulate through the heat jacket 9 to heat the charge in its passage to the internal combustion en-

gine and while I have shown a particular construction of heat jacket, it is, of course, understood that various forms of heat jackets can be employed without departing from the spirit of my invention and therefore I do not wish to limit myself to the particular manner of applying heat to the charge in its passage to the internal combustion engine.

The inlet 10 of the heat jacket 9 is provided with a valve 12 mounted on a stem 13 provided with an arm 14 for operating the same and is what I term a volume regulating valve for controlling the volume of gases passing into the heat chamber of the jacket and is adapted to be operated in conjunction with the controlling mechanism as will be hereinafter fully described.

The end of the exhaust manifold 2 has mounted therein an exhaust throttling valve 15 carried by a valve stem 16 provided with an arm 17 for operating the same, said valve being capable of completely closing the outlet of said exhaust manifold to cause the entire volume of exhaust gases to pass through the heat jacket.

Secured to the end of the exhaust manifold is a coupling 18 from which extends an exhaust pipe 19 to the muffler (not shown) in the usual manner. The coupling 18 is provided with an inlet nipple 20 from which extends a conduit 21 to an outlet nipple 22 formed on the heat jacket 9 of the charge forming device whereby the exhaust gases will be by-passed around the valve 15 when in closed position so as to pass through the heat jacket and heat the explosive charge in its passage to the internal combustion engine.

The charge forming device is provided with a throttle valve 23 carried by a shaft 24 provided with an arm 25 to which is connected an operating rod 26 controlled in the usual manner from the body of the vehicle to which the device is attached.

The main object of this invention is to control the application of heat to a nicety so that the temperature of the charge being formed by the charge forming device can be controlled from the seat of the vehicle to which the device is attached in such a manner that after once being set, the application of heat is controlled by the movement of the throttle valve of the charge forming device and to accomplish this result I arrange on the shaft 24 of the throttle valve 23 a cam 27, which is loosely mounted thereon and is capable of turning on the shaft, the position of said cam being controlled by an operating rod 28 which is connected to a crank 29 provided with a lever 30 working in an indicating plate 31 secured to the dash of the motor vehicle as clearly shown in Figures 1 and 10, whereby the cam can be rotated around the throttle shaft. The construction is such that when the cam is oscillated to shift

its position, it will be held in that position and on the indicating plate 31 I have designated three positions for the lever 30 to assume, but it is, of course, understood that as many positions as desired can be used and means for holding the cam in its adjusted position as will be later described which will prevent the cam from turning after once being adjusted.

10 In the drawing I have shown this cam mounted directly on the throttle shaft 24, but it is, of course, understood that the cam can be mounted adjacent the throttle shaft on a suitable support and operated in the 15 same manner, but I have found that the manner of mounting the cam is simplified by mounting it directly upon the shaft, but I do not wish to limit myself to any particular way and position of mounting the cam.

20 The cam is connected to the arm 14 of the volume valve 13 by a link 32 so that as the cam is adjusted, the position of the valve 13 will be changed, thereby increasing or decreasing the area of the inlet opening of the 25 heat jacket.

The cam is herein shown held in its adjusted position by frictional means which comprises a pin 33 secured in the wall of the heat jacket and extending through a slot 30 34 formed in the cam plate 27, said pin carrying a frictional washer 35 held in frictional contact with the outer face of the cam by coil spring 36 which, allows the cam to be moved by the operating means located on 35 the dash of the motor vehicle to which the device is attached and be retained in its adjusted position.

This is only one form of means for adjusting and holding the cam plate in its adjusted position and I do not wish to limit myself to the use of this particular construction of means as I am aware that various other forms of means for adjusting and holding the cam plate in adjusted position can be 40 used without departing from the spirit of my invention.

The cam plate is provided with a slot 37, the particular formation of which can be changed, but as herein shown it is provided 45 at one end with a substantially vertical portion and a substantially horizontal portion, which gradually terminates in a downwardly extending portion. Slidably mounted within the slot 37 of the cam plate is a member 38 provided with a roller having guide flanges for holding the same in the guide way formed by the slot and can be in the nature of an anti-friction roller to facilitate the movement of the member within the slot.

50 The member 38 is provided with a reduced outer end on which is pivotally mounted a hub 39 provided with a socket 40 in which is secured an operating rod 41 which has its free end pivotally and adjustably connected 55 to the arm 17 of the exhaust gas throttling

valve 15. The member 38 carries a rigid arm 42 which is pivotally connected at its free end to a pin 44 pivotally mounted in the outer end of an arm 45 fixed on one end of the throttle shaft 24 whereby the member 38 travels vertically in the vertical portion of the slot 37 of the cam plate when the throttle valve shaft is oscillated so as to allow the throttle valve to move a predetermined distance before the movement of the arm carried thereby causes the arm of the exhaust throttle valve 15 to move, whereby the exhaust throttle valve 15 will dwell on its seat as the throttle valve opens until a predetermined distance has been reached 70 where the further movement of the throttle valve will cause the exhaust valve to open or move therewith, the movement of the exhaust valve in respect to the throttle valve being determined by the shape and position of the slot in the cam plate. While I have shown a slot of peculiar formation, I am aware that the same can be changed to increase or decrease the distance of travel of the throttle valve before the exhaust throttle 75 valve is moved and therefore I do not wish to limit myself to the details of construction as herein shown as I am aware that various forms of cam plates can be used for guiding the member connecting the throttle valve to the exhaust throttle to cause the exhaust throttle valve to dwell on its seat a predetermined length of time after the throttle valve of the charge forming device has opened a predetermined distance.

80 In the construction shown and thus far described it will be seen that I have provided a heating means control wherein means is provided for completely diverting the exhaust gases out of their natural path of travel through a heating chamber to heat the charge in its passage to the internal combustion engine controlled by the movement of the throttle valve of the charge forming device in connection with adjustable means whereby the volume of exhaust gases delivered to the heating means can be controlled to a nicety so that under different atmospheric conditions more or less heat can be applied as necessary.

85 It will also be noted that the adjusting of the cam operates the volume controlling valve so as to increase or decrease the area of the inlet to the heating chamber so that when the throttle is moved into full open position additional means is provided for cutting off the application of heat to the charge forming device.

90 It will also be noted that in connection with the heating means for heating the charge produced in the charge forming device, I have provided an air heater which is located to the engine side of the exhaust throttle valve and so connected to the air inlet that the air will be heated before being delivered 125 130

to the charge forming device, means being provided for regulating the temperature of the air by an atmospheric air valve.

In the modification shown in Figure 4 the manner of operating the exhaust throttle valve and throttle valve of the charge forming device is identically the same as shown in the preferred form of my invention, but I have found under certain conditions it is advisable to retain a certain volume of exhaust gases in the heating jacket to increase the temperature of the charge being formed and this is accomplished by arranging the volume valve in the outlet nipple 22 of the heat jacket. In this form I have shown the nipple 22' provided with a valve 46 carried by a valve stem 47 provided with an arm 48 connected to the cam 27 by an operating link 49 whereby the movement of the cam in adjusting the same controls the position of the valve.

In the modification of my invention as shown in Figure 5 the construction is substantially the same as shown in Figure 1 with the exception that the volume valve is located in the inlet nipple 20' of the casting of the main exhaust line. In this form I show a valve 50 arranged in the nipple 20' carried by a valve stem 51 which is provided with an arm 52 connected to the cam 27 by a connecting link 53 so as to further retain the volume of heat in the heating chamber of the charge forming device. This construction enables the invention to be applied to other forms and styles of charge forming devices in internal combustion engines and also provides means for offering a resistance to the exhaust gases at the point of connection with the main exhaust line so that a certain amount of back pressure to the passage of the exhaust gases to the heating jacket is obtained in order to retain the volume of heating medium in the heating chamber which I have found under certain conditions is an advantage in carrying out the efficiency of my invention when used in connection with other forms of internal combustion engines and charge forming devices.

In Figure 6 I show still another manner of connecting the volume valve to means operated by the movement of the throttle and in this form I provide the operating rod 41' employed for connecting the throttle exhaust valve to the throttle valve of the charge forming device through the medium of the cam connection, with a member 55 in which is adjustably secured a bolt 56 to which is pivotally connected an operating rod 57 which extends upwardly and is connected to an arm 58 fixed on a shaft 59 carrying a volume valve 60 disposed in an inlet of the heating jacket so that it is moved with the exhaust throttling valve and by the adjustable connection, the relative position of these two valves in respect to their closed positions can be changed,

but in practice I preferably connect the same in such a manner that when the exhaust throttling valve is closed, the valve 60 is wide open or vice versa and I have found that in this construction positive means is provided for completely cutting off the application of heat to the charge forming device by the movement of the throttle as when the throttle is moved into open position and the valve 60 is moved into closed position so as to completely close the exhaust inlet to the heating jacket of the charge forming device.

This construction provides an additional way for connecting up the valves in such a manner that the exhaust throttling valve dwells on its seat a predetermined length of time after the throttle valve of the charge forming device starts in its opening movement, which time is determined by the position of the adjustable cam.

In Figure 7 I have illustrated a form substantially as shown in the preferred embodiment of my invention and to avoid confusion in illustrating the device, I have left off the cam, but it is, of course, understood that the device as here illustrated is to be used in connection with a cam and the heating controlled means as shown in Figures 1, 2 and 3.

In this form the throttle valve shaft 61 of the charge forming device carries an arm 62 which is connected to an arm 63 of the valve stem 64 which is provided with a volume valve 65 by a link 66 so that the valve 65 is moved in unison with the throttle valve. The arm 62 is provided with one or more openings for changing the relative position of said valves in respect to their closed positions so that the movement of these valves in respect to one another can be adjusted, but in practice they are so connected that the valve 65 is in open position when the throttle is closed and is partly or fully closed when the throttle is wide open and as it is interconnected with the main exhaust valve and throttle valve through the medium of the cam, back pressure will be avoided.

In the various figures I have shown the cam plate arranged on one side of the charge forming device and in using my invention in connection with various forms of charge forming devices and internal combustion engines, it is sometimes of an advantage to mount the same on the opposite side of the charge forming device. In order to provide a construction by means of which it can be mounted on either side of the charge forming device in its proper position in respect to the throttle lever thereof, I show in Figure 8 a bearing 67 in which is mounted a shaft 68 having cranks 69 and 70 adjustably mounted on its ends, the crank 69 being connected to the volume valve 71 by a link 72 and the crank 70 to the cam 73 by a link 74, whereby the adjustment of the cam will adjust the position of the valve in the intake of the heating

- jacket and while I have shown certain means for accomplishing the result, I do not wish to limit myself to the mounting of the cam in any particular manner and connecting the same to the valve in any particular manner as
- 5 I am aware that a cam can be mounted in a number of ways to receive a movable member which has a connection to the arm of the throttle valve shaft and the arm of the exhaust throttle valve.
- 10 In Figure 9 I show means for carrying out my invention by connecting the exhaust valve used in a branch leading to the heating jacket to the throttle valve through the medium of a cam and operating member by means of
- 15 which the exhaust valve can be retained in full open position until the throttle valve is moved a predetermined distance and it is illustrated to show the application of my invention to what is known as the Pierce mar-
- 20 vel type of heat control in which the application of heat is controlled by the movement of the throttle.

In the construction of heating means control shown in Figure 9, 75 indicates an exhaust pipe from which extends a branch pipe 76 to a heating chamber 77 of a charge forming device 78 provided with a throttle valve and cam mechanism which is connected by a connecting rod 79 to a valve 80 mounted in the branch pipe as clearly shown so that the valve will remain open until the throttle valve has traveled a predetermined distance.

In Figures 12, 13 and 14, 81 indicates a charge forming device provided with a heat jacket 82 having an inlet nipple 83 from which extends a pipe 84 connected to an outlet nipple 85 of a valve casing 86 adapted to be arranged in the main exhaust line, said 30 valve casing being provided with an exhaust throttling valve 87 carried by shaft 88 on which is mounted an arm 89. The valve casing 86 is provided with an inlet nipple 90 connected to an outlet nipple 91 of the heat jacket by a pipe 92 so that when the main exhaust throttling valve 87 is closed the exhaust gases passing through the main exhaust line will be by-passed around the valve 87 so as to travel through the heat jacket 50 of the charge forming device.

The charge forming device is provided with the usual throttle valve 93 carried by a throttle valve shaft 94 on which is mounted a cam plate 95. The cam plate is provided 55 with an ear 96 having a series of openings formed therein in one of which is adapted to be loosely secured an operating rod 97 connected at its other end to an arm 98 carried by a shaft 99 which is provided with a volume valve 100 arranged in the inlet nipple 90 of the valve casing 86 so that the adjustment of the cam to change the position of the volume valve will regulate the volume of gases passing through the heat jacket. The 60 shaft 94 is provided with an arm 101 carry-

ing a pin to which is connected an arm 102 carried by guide member 103 working in the slot of the cam, said guide member being connected to the arm 89 of the exhaust throttle valve by a link 104 in a similar manner as previously described so that when the throttle valve is operated, the exhaust throttle valve will dwell on its seat a predetermined length of time dependent upon the position of the cam.

In Figures 14 and 15 I have shown the cam adjusted in two positions so as to change the relative movement of the throttle valve and the exhaust throttling valve as well as the volume valve and it is, of course, understood that when the cam is adjusted from the dash, the position of the volume valve is changed but the charge throttling valve and the exhaust throttling valve are not moved. The position of the cam after once being adjusted determines the movement of the exhaust throttling valve by the opening movement of the charge throttling valve so that when the cam is in the position shown in Figure 12, when the throttle valve is operated, the guide member moves vertically a predetermined distance without exerting a pull on the arm of the exhaust throttle valve, whereby the exhaust throttle valve remains closed while the throttle valve is opened. Upon the further movement of the throttle valve, the guide member travels from the vertical portion of the slot into the substantially horizontal portion and starts to open the main exhaust throttle.

It will be seen that the shape of the slot can be changed so as to change the relative movement of these valves as with a slot constructed as herein shown to form a guide way, the guide member travels therein in such a manner that the movement of the two valves can be regulated to a nicety and as the guide way is adjustable and capable of being adjusted from the dash, the operator can place the adjustable cam plate in any position desired and after once being positioned, it is held in that position so as to control the movement of the valves to regulate the application of heat. By this particular construction any number of adjustments of the valves can be obtained so as to regulate the opening and closing movement of the controlling valves by the movement of the throttle.

In Figure 16 I show a volume controlling valve 105 arranged in the inlet nipple 106 of the valve casing 107 provided with a shaft 108 carrying an arm 109 which is adjustably connected to the cam 110 by a link 111 and it will be seen that the position of the cam changes the position of the volume valve 105 so as to regulate the size of the opening at the source of supply of the exhaust gases leading to the heat jacket of the charge forming device.

In Figure 17 I show a volume controlling

valve 112 disposed in the outlet nipple 113 of the heat jacket 114. The valve carries an arm 116 which is adjustably connected to the cam plate 117 by a link 118 which controls the inlet for the exhaust gases by the adjustment of the cam.

In Figure 18 I show a valve 119 arranged within the outlet nipple 120 of the heat jacket 121 of the charge forming device having an arm 122 adjustably connected to the cam 124 by a link 125 so as to hold a certain volume of exhaust gases in the heat jacket.

In the preferred embodiment of my invention I have shown an air heater disposed over the main exhaust line so that the air is heated by the exhaust gases and conveyed to the charge forming device so that the position of the exhaust throttling valve determines the temperature of the air delivered to the charge forming device as the air heater is arranged on the engine side of the exhaust throttling valve and in connection with the additional air inlet I am able to regulate the temperature of air delivered to the charge forming device.

While I have shown a particular construction of air heater and the particular position of the same, I am aware that various other constructions of air heaters can be used and the same can be placed in different positions without departing from the spirit of my invention.

In Figure 19 I show a construction of damper control substantially the same as shown in Figure 4, in which 126 indicates the main exhaust, 127 the heat jacket arranged to heat the charge in its passage to the internal combustion engine having an outlet pipe 128 connected to the exhaust pipe 126 to the muffler side of the throttling exhaust valve 129, which is controlled by the movement of the throttle through the medium of a cam as clearly described in the description of Figure 4. The outlet pipe 128 is provided with a valve 130 connected to the cam 131 whereby the position of the cam determines the position of the valve so as to control the passage of heat through the heating jacket. The heat jacket 127 is shown on the charge forming device 132 which is provided with an air inlet 133. Arranged over the pipe 128 is an air heater 134 so as to heat the air entering the air inlet 133 of the charge forming device and the heat supplied to the charge forming device is influenced by the position of the valve 130 arranged on the outlet of the heat jacket for heating the charge in its passage to the engine.

co In Figure 20 I show an arrangement of valves and heating means substantially as shown in Figure 6, in which 135 is a charge forming device, 136 the heat jacket, 137 the exhaust pipe or manifold provided with an
65 exhaust throttling valve 138 connected to the

inlet valve 139 of the heating chamber, said exhaust valve 138 being controlled by the throttle valve through the medium of the cam 140. The heating jacket 136 is provided with an outlet 141 which is connected to the exhaust 137 to the muffler side of the valve by a pipe 142, said outlet pipe being surrounded by an air heater 143 to supply warm air to the air inlet 144 of the charge forming device 145. 70 75

In Figures 19 and 20 I have shown an air heater disposed around the outlet pipe of the heating jacket for heating the charge in its passage to the engine so that the air delivered to the charge forming device will be heated and in Figure 19 the valve is disposed in the outlet of the heating jacket, while in Figure 20, the valve is disposed in the inlet to the heating jacket and arranged to be operated simultaneously with the main throttle exhaust valve so that the position of these valves influences the heating effect on the warm air stove for heating the air delivered to the charge forming device and I have found by constructing an air heater and placing the same in this position, the position of the valve influences the amount of heat supplied to the warm air stove so that the temperature of the air can be determined and controlled.

In all of the various constructions of manifolds, heat jackets and valve casings herein shown and described, the valves and the operating means are adapted to be interconnected with the throttle valve and the cam plate so as to apply as large a volume of exhaust gases as desired to the heating charge and for as long a time as desired and so arranged that when the throttle valve has opened to any predetermined position from closed to fully open position that the connection between the various valves will operate the valves so as to increase or decrease the application of the heat by the position of the cam plate and while I have shown certain details of construction in connection with the various forms illustrated, I am aware that various changes can be made without departing from the spirit of my invention.

From the foregoing description it will be seen that I have provided heat controlling means for charge forming devices wherein means is provided for diverting the entire volume of exhaust gases from the exhaust manifold through a heating chamber and holding said volume within said heating chamber a predetermined length of time as the throttle valve moves into open position, means being provided for changing the time of applying the application of heat through the medium of a cam which is adjustable from the dash, whereby I am able to cause the exhaust throttling valve to dwell on its seat a predetermined length of time as the throttle valve moves into open position.

It will also be seen that by the use of a volume valve connected to the adjustable cam which controls the movement of the charge throttling valve and exhaust throttling valve, 5 that the volume of exhaust gases passing through the heating chamber is regulated. The position of the volume valve in respect to the inlet and outlet of the heating chamber determines the temperature of the charge and 10 I have shown various ways for accomplishing this result, but it is, of course, understood that I do not wish to limit myself to the forms shown as the installation of a heat control to an internal combustion engine and 15 charge forming device requires various changes according to the design of the motor and charge forming device and therefore I am aware that various changes of construction can be made without departing from 20 the spirit of my invention.

What I claim is:—

1. The combination with an internal combustion engine having an exhaust passage, intake manifold and charge forming device 25 connected thereto, of a heater for heating the charge in its passage to the engine, a valve for controlling the passage of exhaust gases to said heater, a valve for controlling the passage of explosive charge to said engine, 30 a member, a connection between said valves and member and adjustable means arranged in the path of travel of said member to vary the effect of movement of the charge controlling valve on the exhaust controlling valve.

2. The combination with an internal combustion engine having an exhaust passage, intake manifold and charge forming device connected thereto, of a heater for heating the charge in its passage to the engine, a 35 valve for controlling the passage of exhaust gases to said heater, a valve for controlling the passage of explosive charge to said engine, a member for connecting said valves and 40 dash controlled means arranged in the path of travel of said member for adjusting said connection to vary the effect of movement of the charge controlling valve on the exhaust controlling valve.

3. The combination with an internal combustion engine having an exhaust passage, intake passage and charge forming device connected thereto, of a heater for heating the charge in its passage to the engine, a valve for controlling the passage of exhaust gases to said 50 heater, a valve for controlling the passage of explosive charge to said engine, an adjustable guide member, a movable member mounted in said guide member and a connection between said movable member and said valves.

4. The combination with an internal combustion engine having an exhaust passage, intake passage and charge forming device connected thereto, of a heater for heating the charge in its passage to the engine, a passage 55 for supplying exhaust gases to said heater,

an exhaust throttling valve mounted in said exhaust passage, a second valve mounted in the exhaust supplying passage for said heater, a throttle valve for controlling the charge in its passage to the engine, a member 70 connecting said throttling valves and means for guiding said member to vary the effect of movement of the throttle valve on the exhaust throttling valve.

5. The combination with an internal combustion engine having an exhaust passage, intake passage and charge forming device connected thereto, of a heater for heating the charge in its passage to the engine, said heater being in communication with the exhaust passage, a throttle valve for said charge forming device, a throttle valve for said exhaust passage, an adjustable plate disposed adjacent the throttle valve of said charge forming device, a member movably mounted in said plate and 80 means for connecting said member to the charge and exhaust throttling valves.

6. The combination with an internal combustion engine having an exhaust passage, intake passage and charge forming device connected thereto, of a heater for heating the charge in its passage to the engine, a valve for throttling the passage of exhaust gases through said exhaust passage, means for conveying the exhaust gases from said passage to said heater, a volume valve for controlling the passage of exhaust gases through said heater, a throttle valve for said charge forming device, a plate provided with a slot disposed adjacent said charge forming device, a member mounted in said plate and having a connection with the valves for throttling the exhaust and explosive charge, a connection between said plate and said volume valve and means for adjusting the position of said plate to vary the effect of movement of the throttle valve on the exhaust throttling valve.

7. The combination with an internal combustion engine having an exhaust passage, intake passage and charge forming device connected thereto, of a heater for heating the charge produced by said charge forming device, means for throttling the exhaust gases causing said gases to pass through the heater, means for regulating the volume of exhaust gases passing through said heater, a throttle valve for said charge forming device, a member connecting said throttling valves, means for connecting said connection to said volume valve and adjustable means for guiding said member to vary the effect of movement of the charge throttling valve on the exhaust throttling valve.

8. The combination with an internal combustion engine having an exhaust passage, intake passage and charge forming device connected thereto, of a heater for heating the charge in its passage to the internal combustion engine, a duct for supplying exhaust 130

- gases from said exhaust passage to said heater, a valve in said exhaust passage, means for supplying warm air to said charge forming device, a throttle valve for said charge forming device, means for varying the volume of exhaust gases passing through said heater, a member connecting said valves and means for guiding said member to vary the effect of movement of the throttle valve on the exhaust valve.
9. The combination with an internal combustion engine having an exhaust passage, intake passage and charge forming device connected thereto, of a heater for heating the charge in its passage to the engine, an exhaust throttle valve for said exhaust passage, a throttle valve for the intake passage, an adjustable member provided with a slot, a movable member working in said slot, a connection between said movable member and said valves and dash controlled means for adjusting said adjustable member to vary the effect of movement of the throttle valve on the exhaust throttling valve.
10. The combination with an internal combustion engine having an exhaust passage, intake passage, charge forming device and means for heating the charge in its passage to the engine, of valve controlled means for supplying exhaust gases to said heating means, a throttle valve for said intake passage, a cam plate disposed to one side of said throttle valve, a member movably mounted in said cam plate, a connection between said throttle valve and the valve controlling heating means and means for adjusting said cam plate to vary the effect of movement of the throttle valve on the exhaust gas controlling valve.
11. The combination with an internal combustion engine having an exhaust passage, intake passage, charge forming device and means for heating the charge in its passage to the internal combustion engine, of means for controlling the application of heat to said heating means comprising a valve arranged in the exhaust passage, a throttle valve for said intake passage, a plate provided with a slot arranged to one side of said throttle valve, a member slidably mounted in said slot, a connection between said member and said valve, and dash controlled means for adjusting said plate to vary the effect of movement of the throttle valve on the exhaust controlled valve.
12. The combination with an internal combustion engine, of a carburetor, means for furnishing a supply of warm air thereto, means for heating the explosive charge in its passage to the internal combustion engine, a throttle valve for said carburetor, a duct for conveying exhaust gases from said engine to said heating means, means for throttling the exhaust gases to cause said gases to pass through said duct, an adjustable guide disposed adjacent said carburetor, a member movably mounted in said guide having a connection with said valves and means for adjusting said member to allow said exhaust throttling valve to dwell on its seat on the initial movement of said throttle valve.
13. In heat controlled means for internal combustion engines, the combination with a pair of valves arranged to throttle the exhaust gases and explosive charge, of an adjustably mounted plate, a member movably mounted in said plate, a connection between said member and said valves and means for adjusting said plate to vary the effect of movement of the throttle valve on the exhaust valve to allow said exhaust valve to dwell on its seat in the opening movement of said throttle valve.
14. The combination with an internal combustion engine having an exhaust passage, intake passage and charge forming device connected thereto, of a heater for heating the charge in its passage to the engine, a duct connecting said heater to said exhaust passage, a valve in said exhaust passage, a throttle valve for said charge forming device, an adjustable plate provided with a slot arranged adjacent said charge forming device, a member movably mounted in said adjustably mounted plate, a connection between said member and said exhaust and charge throttle valves, a volume valve for controlling the passage of said gases through said heater, a connection between said plate and said volume valve to adjust the relative position of said valve and means for adjusting said plate to vary the effect of movement of the throttle valve on the exhaust throttling valve.
15. The combination with an internal combustion engine having an exhaust passage, intake passage and charge forming device connected thereto, of a heater arranged to heat the charge in its passage to the internal combustion engine, a duct for supplying exhaust gases from said exhaust passage to said heater, a valve in said exhaust passage, a throttle valve for said charge forming device, means for supplying warm air to said charge forming device, a valve for controlling the volume of exhaust gases passing through said heater, a plate provided with a cam slot, a member movably mounted in said plate, a connection between said member and said exhaust and throttle valves, a connection between said plate and volume valve, and means for adjusting the position of said plate to vary the effect of movement of the throttle valve on the exhaust throttling valve.
16. The combination with an internal combustion engine having an exhaust passage, intake passage and charge forming device connected thereto, of a heater arranged to heat the charge in its passage to the internal combustion engine, a duct for supplying ex-

haust gases from said exhaust passage to said heater, a valve in said exhaust passage, a throttle valve for said charge forming device, an air heater for supplying warm air to said charge forming device, an adjustable guide member having a connection with the valve for controlling the volume of exhaust gases passing through said heater and a member slidably mounted in said guide member having a connection with the throttle valve and the exhaust throttling valve.

17. The combination with an internal combustion engine having means for heating the explosive charge in its passage to the engine, of a throttle valve for controlling the passage of the heating medium to said heating means, a throttle valve controlling the charge delivered to the engine, a plate provided with a cam slot, a member slidably mounted in said cam slot, a connection between said member and said throttling valves and means for adjusting said plate to vary the effect of movement of the charge throttling valve on the exhaust throttling valve.

25 18. The combination with an internal combustion engine having an exhaust passage, intake passage and charge forming device connected thereto, of a heater for heating the charge in its passage to the internal combustion engine, a throttle valve for said intake passage carried by a shaft provided with an arm, a plate loosely mounted on said shaft having a cam slot, a member mounted in said cam slot, a valve controlling the passage of heating medium to said heater, a connection between said slidably mounted member and the throttle valve arm and said heating medium control valve and means for adjusting said plate to vary the effect of movement of the throttle valve on the heating medium valve.

45 19. The combination with an internal combustion engine having an exhaust passage, intake manifold and charge forming device connected thereto, of a heater for heating the charge in its passage to the engine, a valve for controlling the passage of exhaust gases to said heater, a valve for controlling the passage of explosive charge to said engine, a member having a connection with said valves and means arranged in the path of travel of said member to vary the effect of movement of the charge throttling valve on the exhaust throttling valve.

55 20. The combination with an internal combustion engine having an exhaust passage, intake manifold and charge forming device connected thereto, of a heater for heating the charge in its passage to the engine, a valve for controlling the passage of exhaust gases to said heater, a valve for controlling the passage of explosive charge to said engine, a member having a connection with said valves, movable means arranged in the path of travel of said member to vary the effect of move-

ment of the charge throttling valve on the exhaust throttling valve and means for adjusting said means.

21. The combination with an internal combustion engine having an exhaust passage, intake passage and charge forming device connected thereto, of a heater for heating the charge in its passage to the engine, a valve for regulating the volume of exhaust gases passing through said heater, a throttle valve for the exhaust passage, a throttle valve for the intake passage and a member having a connection with said throttle valve and an adjustable member arranged in the path of travel of said member to vary the effect of movement of the charge throttling valve on the exhaust throttling valve.

70 22. The combination with an internal combustion engine having an exhaust passage, intake passage and charge forming device connected thereto, of a heater for heating the charge in its passage to the internal combustion engine, a duct for supplying exhaust gases from said exhaust passage to said heater, a valve in said exhaust passage, a warm air stove for supplying warm air to said charge forming device, a throttle valve for said charge forming device, a connection between said throttle valve and exhaust valve, means for varying the volume of exhaust gases passing through said charge heater, said means controlling the temperature of the air delivered from said warm air heater and means to vary the effect of movement of the throttle valve on the exhaust valve.

75 23. The combination with an internal combustion engine having an exhaust passage, intake passage and charge forming device connected thereto, of a heater arranged to heat the charge in its passage to the internal combustion engine, a heater arranged to heat the air delivered to the charge forming device, a valve for controlling the passage of exhaust gases through said exhaust passage, a valve for controlling the volume of exhaust gases passing through the charge heater, a throttle valve for said charge forming device, a member connecting said throttle valve to the valve of the exhaust passage and means for varying the effect of movement of the charge throttling valve on the exhaust throttling valve.

80 24. The combination with an internal combustion engine having an exhaust passage, intake passage and charge forming device connected thereto, of a heater arranged to heat the charge in its passage from the internal combustion engine, a duct for supplying gases from the exhaust passage to said heater, an air heater arranged to be heated by the exhaust, a valve in said duct and means for operating said last mentioned valve to vary the heating effect of the exhaust gases on the charge and air delivered to said charge forming devices.

25. The combination with an internal combustion engine having an exhaust passage, intake passage and charge forming device connected thereto, of a heater for heating the charge in its passage to the engine, a duct extending from the exhaust passage to said heater, an air heater arranged in the path of passage of said exhaust, a valve for controlling the volume of exhaust gases passing through said heater and means for adjusting the position of said valve to vary the effect of the heat for heating the charge and the air passing to said charge forming device.
26. The combination with an internal combustion engine having an exhaust passage, intake passage and charge forming device connected thereto, of a heater arranged around the intake passage, means for bypassing the exhaust gases through said heater, an air heater arranged around said bypass, a valve for regulating the volume of exhaust gases passing through said heater and means for adjusting said valve to vary the heating effect on the charge and the air delivered to said charge forming device.
27. The combination with an internal combustion engine having an exhaust passage, intake passage and charge forming device connected thereto, of a heater arranged to heat the charge in its passage to the internal combustion engine, a valve in said exhaust passage, passages connecting said heater to said exhaust to each side of said valve, a valve arranged in one of said passages for regulating the volume of exhaust gases passing through said heater, an air heater arranged around one of said passages arranged to deliver warm air to said charge forming device, means operated by the movement of the throttle valve for controlling the position of the exhaust valve and means inter-connected with said means for changing the position of said volume valve for adjusting the heating effect of the charge heater and air heater.
28. In a heat control for internal combustion engines, the combination with valves arranged to throttle the exhaust gases and explosive charge, means for connecting said valves and means arranged in the path of travel of said connecting means to vary the effect of movement of the charge controlling valve on the exhaust controlling valve.
29. The combination with an internal combustion engine having an exhaust passage, intake manifold and charge forming device connected thereto, means for heating the charge in its passage to the engine, a valve controlling the passage of exhaust gases to said heating means, a valve controlling the passage of explosive charge to said engine, an oscillating member having a connection with said valves and adjustable means arranged in the path of travel of said oscillating member to vary the effect of movement of the charge controlling valve on the exhaust controlling valve.
30. The combination with an internal combustion engine having an exhaust passage, intake passage and charge forming device connected thereto, of a heater for heating the charge in its passage to the engine, means for controlling the passage of exhaust gases to said heater, means for controlling the passage of explosive charge to said engine, a connection between said exhaust gas controlling means and said explosive charge controlling means and means arranged in the path of travel of said connecting means to vary the volume of exhaust gases passing to said heater.
31. The combination with an internal combustion engine having an exhaust passage, intake passage and charge forming device connected thereto, means for heating the charge in its passage to the internal combustion engine, means for controlling the passage of explosive charge to said engine, means for controlling the application of heat to said heating means, means connecting the last-mentioned means to the means for controlling the passage of the charge to the engine and an adjustable member arranged to vary the volume of the heating means in respect to the charge controlling means.
32. The combination with an internal combustion engine having an exhaust passage, intake passage, and charge forming device connected thereto, a heater for heating the charge in its passage to the engine, means for controlling the passage of exhaust gases to said heater, means for controlling the passage of explosive charge to said engine, a connection between said exhaust gas controlling means and said explosive charge controlling means and means arranged in the path of travel of said connecting means to vary the heating effect of the exhaust gases on the explosive charge in its passage to the internal combustion engine.
- In testimony whereof I hereunto affix my signature.
- WALTER G. HEGINBOTTOM.
